UNITED STATES PATENT OFFICE

136,462

DESIGN FOR A SUPPORTING DEVICE FOR A DISH, PLATE, OR THE LIKE

Henry D. Noel, New York, N. Y.

Application February 3, 1943, Serial No. 109,417

Term of patent 14 years

To all whom it may concern:

Be it known that I, Henry D. Noel, a citizen of the United States, residing at New York, in the county of New York and State of New York, have invented a new, original, and ornamental Design for a Supporting Device for a Dish, Plate, or the like, of which the following is a specification, reference being had to the accompanying drawing, forming part thereof.

Figure 1 is a perspective view of a supporting device, for a dish, plate or the like, showing my new design.

I claim:

The ornamental design for a supporting device for a dish, plate, or the like, as shown.

HENRY D. NOEL.
